ATTACHING DEVICE

Filed Dec. 3, 1927

UNITED STATES PATENT OFFICE

RALPH S. PEIRCE, OF HINSDALE, ILLINOIS

ATTACHING DEVICE

Application filed December 3, 1927. Serial No. 237,476.

My invention relates to attaching devices of the class employing bolts and object holding elements in the form of bars along and against the sides of which the bolts are hammer driven.

In accordance with one feature of the invention, the object holding bar is provided with a head at its outer end which projects laterally from the bar to lap the supported object and there is a liner of soft metal upon the body of the bar which is interposed between the bolt and the bar and with which the bolt was forcible lateral engagement whereby the bar is firmly held in position, it being assumed that the entire device is received within a recess in a wall or other support prior to the time that the bolt is hammered into place to force the device as a whole into tight engagement with the wall or support. In the preferred embodiment of the invention, there are two such bars which collectively form a split sleeve.

In accordance with another feature of the invention, the object holding bar or sleeve has an aperture therethrough and there is another liner on the other side of the bar or, in case of a sleeve, on the outside of the sleeve, both liners having a portion in integral connection therewith and passing through said aperture.

In accordance with another feature of the invention, a depression is formed on the exterior side of the sleeve or on the side of the bar opposite the side that is adjacent the bolt, there being a body of softer metal which substantially fills the depression, the bolt forcibly engaging the bar or sleeve on the side opposite said depression and in the zone of the depression where the bolt forcibly engages the bar or sleeve to thereby spread and press the body of softer metal that is in the depression against the surrounding wall or support.

In accordance with another feature of the invention, the bar or sleeve is thickened at one end, preferably by folding the same upon itself, this thickened end being encountered by the hammer driven bolt to deflect or spread the bar or sleeve in the process of securing the attaching device to the wall or support.

Where the bar or sleeve is thickened by folding it upon itself, the sides of the fold are preferably spaced sufficiently apart to receive a body of softer metal therebetween, the bar being apertured through the exterior side of the fold to permit this softer metal to be exuded therethrough when the sides of the fold are brought closely together by the hammered bolt, the exuded metal being forced toward the wall or support and cooperating to hold the fastening element in place.

The invention will be explained more fully by reference to the accompanying drawings in which Fig. 1 is a side view of one form of hammer driven bolt which may be employed; Fig. 2 is a perspective view of the split sleeve into which the bolt shown in Fig. 1 may be driven, the depression extending longitudinally of the sleeve being illustrated with a body of softer metal therein; Fig. 3 is a perspective view showing the halves of the structure shown in Fig. 2 in separated relation, the fillings in the depressions in the sides of the sleeve being omitted; Fig. 4 is a view from the interior showing one half of the sleeve with the soft metal absent; Fig. 5 is a cross sectional view taken through both halves of the sleeve and showing the softer metal in place, the bolt being absent; Fig. 6 is a view generally similar to Fig. 5 but showing the bolt driven into place; Fig. 7 is a sectional view on line 7—7 of Fig. 5; and Fig. 8 is a sectional view on line 8—8 of Fig. 6.

The attaching device illustrated is preferably inclusive of two bars of metal 1 and 2 which are so shaped and arranged as to collectively form a sleeve which is split throughout from end to end into distinct portions and whose bore extends throughout the length of the sleeve. The halves of the sleeve are respectively formed with flange portions 3 and 4 at one end of the sleeve, these flange portions collectively forming a complete flange that surrounds the sleeve. Each flange portion 3, 4 constitutes a head upon the bar which carries it and the two flange portions together constitute a head for the sleeve that is formed of the two bars. This head which thus projects laterally from the sleeve laps the object, 5, Fig. 6, which is to be held by

the attaching device, such object being formed with an opening or recess there-through which receives the sleeve, the sleeve also passing into the suitably sized recess 6 in the wall or support 7 upon which the object 5 is to be secured.

A liner 8 of softer metal is provided upon each bar and within the bore of the sleeve. An assembling bolt 9 preferably in the form of a galvanized nail having a roughened surface throughout its length is forcibly hammered into the bore of the sleeve and against the liner 8, the bolt having strong lateral holding engagement with said liner to prevent the withdrawal of the bolt, this holding engagement being increased by roughening the surface of the bolt, this roughening being preferably secured by suitably galvanizing the bolt. The bolt preferably has a head 9² which may be struck by the hammer and is of wedge formation at its other end, as indicated at 9², to facilitate its entry.

A second liner 10 of softer metal than that of which the sleeve is made is provided upon each bar and upon the exterior of the sleeve. Each bar is formed with an aperture 11 therethrough. In the process of assembling the liners 8 and 10 with each bar, the metal, such as lead, of which these liners are formed, is so poured that a connection 12 uniting the liners will extend through the contiguous aperture 11, the liners and their connection 12 being in integral formation.

Each bar section 1, 2 of the object holding sleeve has a well like depression 13 formed on the exterior side of the sleeve and extending along the same and terminating short of the sides of the bars respectively having the same. When the bolt 9 is hammer driven into position, it will engage the bottom of the depressions 13 and, to a certain extent, flatten out the depressions, consequently expanding the sleeve in the region of the depressions and spreading the expanding soft metal within the depressions whereby the sleeve is tightly held in assembly with the surrounding wall or support. The depression 13 is desirably formed, as here shown, by merely offsetting a portion of the bar laterally, the depression terminating short of the longitudinal side edges of the bar. Thus a depression is formed in the bar without causing a reduction in the cross sectional area of the shank portion of the bar, the shank portion of the bar being of substantially uniform cross sectional area throughout, and the bore of the sleeve is reduced by the depression without weakening the wall of the bar, as would occur if the depression did not stop short of the side edges of the bar.

The inner end of each bar 1, 2, that is, the inner end of the sleeve comprised of these bars, is thickened at the inner end preferably folding the bars upon themselves, the ends

of the bars being desirably directed into the bore of the sleeve, though the invention is not to be thus limited. The thickening of the inner end of the bar is continued lengthwise of the bar to an extent that is in excess of the thickness of the bar whereby an effective obstruction is afforded to counteract the inward exudence of the softer metal. The outer side of the fold in each bar is desirably provided with an aperture 15 extending therethrough and the sides of each fold are desirably spaced sufficiently apart to receive the lower end of the corresponding liner therebetween. When the bolt is driven into place the penetrating end 9² thereof facilitates the entry of the bolt between the depressions 13 and into and through the zone of the folds at 14. The sides of the folds are consequently brought closely together and preferably substantially in contact with each other, the softer metal that was between the sides of the folds being consequently exuded through, the apertures 15 as indicated at 16 in Fig. 6. Some of this metal is also exuded through the cracks between the two bars 1 and 2, as indicated in Fig. 8. The liners 8 in the two bars 1 and 2 are desirably merged into one integral element, the bolt 9 not only forcing the exudence of some of the metal 8 through the cracks between the bars 1 and 2 in the zone at the folds at 14 but also forcing the exudence of some of the metal 8 through these cracks downwardly toward such zone.

It will be seen, particularly with reference to Fig. 6, that the sleeve is very forcibly secured to the surrounding wall or support, the inner and thickened end of the sleeve being especially most effectively assembled due to the formation of the folds at 14 and the employment of the softer metal between the sides of the folds. The thickened inner end of the sleeve also constitutes a stopper or plug for the recess 6 in the wall, such stopper or plug serving to prevent the exudence of the lead or softer material 8 and 10 inwardly beyond this plug whereby the tensing strength or holding power of the fastening device, as a whole, is greatly increased. It will be observed that the inner liner 8 has permanent assembly with the object holding bars 1 and 2 so that both these bars are, thereby, held in assembly before they are put into service. In other words, the thickened inner end not only obstructs the inward exudence of the softer material 8, but, in cooperation with the bolt 9 and the wall of the recess 6, obstructs also the inward exudence of the softer material 10, since the bolt, upon engaging the folds 14 positively separates the inner ends of the bars 1 and 2, forcing the inner ends of the bars laterally to substantially fill the space between the bolt and the recess.

Changes may be made without departing from the invention.

Having thus described my invention, I claim:

1. An attaching device including an object holding bar of metal having an object engaging flange at one end that is to be outermost; a body of softer metal upon one side of said bar; and a driven bolt extending along the opposite side of the bar and forcibly pressing thereagainst wherein the side of the bar that is engaged by the bolt is also provided with a liner of softer metal that is directly engaged by the bolt and through which pressure from the bolt is transmitted to the bar, the softer bodies of metal upon both sides of the bar being integral and having a connecting portion passing through an opening that is formed through the bar.

2. An attaching device including an object holding bar of metal having an object engaging flange at one end that is to be outermost; a body of softer metal upon one side of said bar; and a driven bolt extending along the opposite side of the bar and forcibly pressing thereagainst wherein the bar is folded at its inner end to thicken it and wherein the side of the bar that is engaged by the bolt is also provided with a liner of softer metal that is directly engaged by the bolt and through which pressure from the bolt is transmitted to the bar, the softer bodies of metal upon both sides of the bar being integral and having a connecting portion passing through an opening that is formed through the bar.

3. An attaching device including an object holding bar of metal having an object engaging flange at one end that is to be outermost; a body of softer metal upon one side of said bar; and a driven bolt extending along the opposite side of the bar and forcibly pressing thereagainst wherein the bar is folded at its inner end to thicken it, wherein the bar carries a portion initially engaged by and sloping inwardly toward the bolt, and wherein the side of the bar that is engaged by the bolt is also provided with a liner of softer metal that is directly engaged by the bolt and through which pressure from the bolt is transmitted to the bar, the softer bodies of metal upon both sides of the bar being integral and having a connecting portion passing through an opening that is formed through the bar.

4. An attaching device including two separately formed objects holding bars of metal placed abreast and each having an object engaging flange at one end that is to be outermost; and a liner of softer metal upon the opposed sides of said bars and holding the bars in assembly, and engageable by a bolt driven between the bars, each bar being thickened at its other end to prevent the inward exudence of the liner.

5. The structure of claim 4 wherein the bars are folded at their inner ends to thicken them.

6. The structure of claim 4 wherein the

liner has the portion thereof that is initially engaged by the bolt sloping inwardly toward the bolt.

7. An attaching device including an object holding bar of metal having an object engaging flange at one end that is to be outermost, said bar being folded at its other end; and a liner of softer metal for the bar having a portion between the body of the bar and its folded end portion, there being an aperture in the outer side of the fold communicating with the space occupied by said liner portion through which this portion may exude.

8. An attaching device including two separately formed object holding bars of metal placed abreast and each having an object engaging flange at one end that is to be outermost; and a liner of softer metal upon the opposed sides of said bars and holding the bars in assembly, and engageable by a bolt driven between the bars.

9. An attaching device including an object holding bar of metal having an object engaging flange at one end that is to be outermost, said bar being folded at its other end and having an aperture in the outer side of the fold; a liner of relatively soft metal having a portion between the sides of said fold and another portion extending laterally through said aperture; and a driven bolt extending along the bar into engagement with the folded end of the bar and forcibly pressing the sides of the fold together, whereby said soft metal is forcibly pressed into engagement with said object to which the bar is applied.

10. The combination with a recess; of an attaching device embodying two object holding bars of metal placed abreast and each having an object engaging flange at one end that is to be outermost, each bar having a depression in one side, a body of softer metal in each depression, each bar being thickened at its other end that is to be innermost to an extent lengthwise of the bar in excess of the thickness of the bar, said depressions terminating short of the thickened portions of the bars, and a driven bolt extending along said bars and forcibly pressing against the sides thereof opposite the sides having the depressions and engaging the thickened portions to separate the bars, said thickened portions extending between the bolt and the walls of the recess, whereby said thickened portions cooperate with the bolt and the wall of the recess to obstruct the inward exudence of the softer metal.

11. An attaching device embodying an object holding element in the form of an elongated integral bar of metal having a shank portion and a flange portion, said flange portion being at one end of the bar that is to be outermost and said shank portion being of substantially uniform cross sectional area throughout, a portion of said

bar intermediate the ends of the bar being offset to provide a depression terminating short of the side edges of the bar in one side of the bar and the bar being provided with 5 a body of softer metal substantially filling said depression.

In witness whereof, I hereunto subscribe my name.
